K. C. UNDERWOOD, J. E. CRANE, AND J. M. KESSLER.

APPARATUS FOR USE IN TREATING CELLULOSE COMPOSITIONS WITH SOLVENT VAPORS.

APPLICATION FILED MAY 2, 1919.

1,412,762.

Patented Apr. 11, 1922.

UNITED STATES PATENT OFFICE.

KENNETH C. UNDERWOOD, OF NEWARK, NEW JERSEY, JASPER E. CRANE, OF WILMINGTON, DELAWARE, AND JOHANNES M. KESSLER, OF WEST ORANGE, NEW JERSEY, ASSIGNORS TO E. I. DU PONT DE NEMOURS & COMPANY, OF WILMINGTON, DELAWARE, A CORPORATION OF DELAWARE.

APPARATUS FOR USE IN TREATING CELLULOSE COMPOSITIONS WITH SOLVENT VAPORS.

1,412,762.

Specification of Letters Patent. Patented Apr. 11, 1922.

Application filed May 2, 1919. Serial No. 294,326.

To all whom it may concern:

Be it known that we, KENNETH C. UNDERWOOD, a citizen of the United States, of Newark, in the county of Essex and State of New Jersey; JASPER E. CRANE, a citizen of the United States, of Wilmington, in the county of New Castle and State of Delaware, and JOHANNES M. KESSLER, a citizen of Germany, of West Orange, in the county 5 of Essex and State of New Jersey, have invented a certain new and useful Improvement in Apparatus for Use in Treating Cellulose Compositions with Solvent Vapors, and do hereby declare that the following 10 is a full, clear, and exact description thereof.

Our invention relates particularly to an apparatus by means of which cellulose compositions may be treated with solvent vapors for the purpose of providing smooth 15 surfaces for the same.

The object of our invention is to provide an apparatus by means of which cellulose compositions, and particularly compositions which have been made from cellulose 20 plastics, such for example as pyralin or celluloid, may be treated with solvent vapors, as for example, vapors of methyl alcohol, so that the surfaces thereof will be sufficiently softened in this manner to enable them to be provided with smooth 25 surfaces, by the application of pressure from a highly polished plate. In the manufacture of sheets of cellulose compositions, as for example, pyralin or celluloid, it is customary to cut said sheets from a pressed 30 block of said material. The cutting of these sheets, however, leaves certain knife marks which it is necessary to remove, as otherwise there would remain upon the 35 sheets ridges rendering the surfaces thereof rough and semi-opaque when made from transparent materials. It is the object of our invention especially to provide a convenient, effective and economical apparatus 40 by means of which these knife marks and similar unevennesses in the surfaces of these sheets may be removed. A further object is to treat the sheets of material at a constant and greater velocity and more 45 uniformly than formerly. Another object is to avoid the detrimental effects due to

the presence of moisture, which if present produces white spots owing to the precipitation of pyroxylin in the pyralin or celluloid. Still another object is to obtain increased 55 efficiency owing to the absence of danger to the health of the workmen because of vapors escaping into the atmosphere.

In general, our invention comprises an apparatus which is designed to apply to such 60 sheets of material a current of heated solvent vapors, such for example as methyl alcohol vapors, so as to superficially soften the surfaces of the same, while at the same time effectively recovering unused vapors 65 supplied to the apparatus, including the vapors which are adjacent to the treated surfaces, but which have not entered the same. Further objects of our invention 70 will appear from the detailed description thereof contained hereinafter.

While our invention is capable of embodiment in many different forms, for the purpose of illustration we have shown only one 75 form of our invention in the accompanying drawings, in which;

Fig. 1 is a rear elevation of an apparatus made in accordance with our invention, and

Fig. 2 is a vertical section through a portion of the same.

In the drawings, we have shown a plurality of uprights 1, having a platform 2 thereon, supporting an alcohol vaporizer 3, which is shown as provided with a steam inlet pipe 4, a steam outlet pipe 4^a, and 80 an alcohol level gage 5. Said vaporizer is preferably connected by means of a pipe 6 to a narrow vapor applying chamber 7 having a steam jacket 8 surrounding the same, which is shown as provided with a 85 steam pipe 9. Said vapor applying chamber 7 preferably has entering the same an inlet opening 11 and an outlet opening 12, which are provided with lower and upper guide plates 13 and 14 having perforations 15 and 16 respectively to permit the passage through the same of the methyl alcohol vapors. The 90 guide plates 13 and 14 are designed to guide sheets of a nitrocellulose composition, such for example as pyralin or celluloid 17, which are preferably forced through the same by 95 means of a pair of heated rollers 18 and 19

heated with a current of steam supplied by means of inlet and outlet pipe 20 and 20^a, the interiors of said rollers being shown as connected by means of a pipe 21 through 5 swing joints or glands 20^b located at the other end thereof. In advance of the rollers 18 and 19 there are shown two additional guide plates 21^a and 21^b to guide the sheets 17. The rollers 18 and 19 are shown as 10 driven by a gear 22 meshing with a pair of gears 23 and 24 on the rollers 19 and 18 respectively. The gear 22 preferably has attached thereto a sprocket 25 carrying a chain 26 which, in the embodiment shown, 15 passes over a sprocket 27 on a shaft 28, which shaft 28 carries a pulley 29, driven by a belt 30 from a motor shaft 31, carrying another pulley 32. Adjacent to the lower and upper outlet opening guide plates 20 13 and 14, there are shown two suction boxes 33 and 33^a having perforations 34 communicating with the opening 12, said boxes being shown as connected by a pipe 35 to the suction side of a suction pump 36, driven 25 by a pulley 37 and a belt 38 from a pulley 39 on the motor shaft 31. The vapors which are thus drawn into the pump 36 may pass out by a vapor pipe 41 to a coil condenser 42 supplied with an agent such as cooling 30 water by means such as pipes 43 and 44. The condensed methyl alcohol preferably passes out from the condenser by a pipe 45, and any uncondensed vapors may escape by a pipe 46 therefrom, to be recovered in any 35 suitable way, if desired.

In the operation of the described embodiment of our invention, sheets of pyralin or celluloid 17 are fed between the guide plates 21^a and 21^b to the heated rollers 18 and 19. 40 These rollers are heated to prevent condensation of alcohol vapor with consequent softening and sticking of portions of the pyralin or celluloid sheets 17 thereto, inasmuch as such condensation, softening and adhesion 45 would occur if the rollers were not heated. They, furthermore, force the sheets through the chamber 7 in the desired direction over the perforations 15 and 16, so that a current of the heated methyl alcohol vapors is 50 brought into contact with the under and upper surfaces thereof. As each sheet 17 passes out of the chamber 7, it is brought through the suction boxes 33 and 33^a, where any vapors adjacent the surfaces of the sheets 55 are removed, and are conducted to the suction pump 36, and driven by the same into the condenser 42. The condensed methyl alcohol is collected from the pipe 45, while the residual methyl alcohol vapors are 60 conveyed away by the pipe 46 for recovery or not in any suitable manner, as desired. The surfaces of these sheets having now been softened by the application of the solvent vapors, said sheets are subjected to pressure 65 between polished metal plates, so that in this

way all of the superficial roughnesses present in the plates as they come from the cutters are removed.

While we have described our invention above in detail, we wish it to be understood 70 that many changes may be made therein without departing from the spirit thereof.

Claims:

1. An apparatus comprising a solvent vapor applying chamber, means for passing a 75 sheet of a nitrocellulose composition therethrough, and means to recover vapors which do not pass away with the sheet.

2. An apparatus comprising a solvent vapor applying chamber, means for passing a 80 sheet of a nitrocellulose composition therethrough, and means to recover vapors which do not pass away with the sheet, comprising a vapor outlet pipe from said chamber, and means directly connected therewith to condense said vapors obtained therefrom.

3. An apparatus comprising a solvent vapor applying chamber, means for passing a sheet of a nitrocellulose composition therethrough, and means to recover vapors which 90 do not pass away with the sheet comprising a suction device adjacent the point of exit of the sheet from said chamber, and means directly connected therewith to condense said vapors obtained therefrom.

4. An apparatus comprising a solvent vapor applying chamber, means for passing a sheet of material therethrough comprising plates containing perforations positioned within the chamber, and rollers provided with heating means, said rollers being mounted to feed the sheet in between the said plates.

5. An apparatus comprising a solvent vapor applying chamber, means for passing a 105 sheet of material therethrough comprising plates containing perforations positioned within the chamber, rollers provided with heating means, said rollers being mounted to feed the sheet in between the said plates, 110 and plates for guiding the sheet to and from the rollers.

6. An apparatus comprising a vapor applying chamber, a plate within the chamber having a perforation therein to guide a sheet 115 of a nitrocellulose composition while being subjected to said vapors, and heated rollers for feeding said sheet into the chamber, and means to recover solvent vapors comprising a suction device adjacent the point of 120 exit of the sheet from the chamber and a condenser connected thereto.

7. An apparatus comprising a solvent vapor applying chamber, means for passing a sheet of material therethrough comprising 125 plates containing perforations positioned within the chamber, rollers provided with heating means, said rollers being mounted to feed the sheet in between the said plates, plates for guiding the sheet to and from the 130

rollers, and means to recover solvent vapors comprising a suction device adjacent the point of exit of the sheet from the chamber and a condenser connected thereto.

- 5 8. An apparatus comprising a vapor applying chamber, a plate within the chamber having a perforation therein to guide a sheet of a nitrocellulose composition while being subjected to said vapors, rollers provided
10 with heating means for feeding said sheet into the chamber, and guides for conducting

said sheets to the rollers and from the rollers to the plate with the opening.

In testimony that we claim the foregoing we have hereunto set our hands.
